UNITED STATES PATENT OFFICE.

ADOLPH PETZOLD, OF PHILADELPHIA, PENNSYLVANIA, ASSIGNOR TO JOHN BROMLEY & SONS, OF SAME PLACE.

DESIGN FOR A RUG.

SPECIFICATION forming part of Design No. 19,336, dated October 1, 1889.

Application filed August 19, 1889. Serial No. 321,178. Term of patent 3½ years.

To all whom it may concern:

Be it known that I, ADOLPH PETZOLD, a citizen of the United States, and a resident of Philadelphia, Pennsylvania, have invented a new and original Design for Rugs, of which the following is a description, reference being had to the accompanying photographic illustration, making a part hereof.

The leading features of my design are an elongated center piece, the outer edges of which at the sides are ornamented with figures resembling the "fleur-de-lis," with scroll-work at each end coming nearly to a point. In the middle of this center piece is an ornamental scroll figure, and the "ground" without the center piece is ornamented at intervals with small figures at the corners and four sides.

A is the elongated center piece; B, the side figures bearing a general resemblance to the fleur-de-lis; C C, the end scroll-work; D, the middle ornamental scroll figure; E E, the side small figures; F F, the corner figures.

What I claim is—

The design for a rug, composed of the ornamental center figure or piece elongated, as shown, side ornamental figures B, resembling in general outline the fleur-de-lis, end scroll-work C C, middle ornament D, and side and corner ornamental figures E E F F, substantially as shown.

ADOLPH PETZOLD.
